UNITED STATES PATENT OFFICE

2,149,868

GLOW PLUG

Hector Rabazzana, Flint, Mich., assignor to General Motors Corporation, Detroit, Mich., a corporation of Delaware

Application November 14, 1935, Serial No. 49,845

11 Claims. (Cl. 123—145)

My invention relates to glow plugs wherein a wire of high resistance is heated to incandescence by a current of electricity of low voltage, the heated wire being located within the cylinder of

5 an internal combustion engine and the purpose thereof being to ignite the combustible mixture therein. Such plugs are used principally in Diesel engines to ignite the combustible mixture when the engine is being started and are commonly 10 rendered inactive by breaking the circuit in which they are included after the engine is in operation; as in such engines the ignition of the fuel supplied to the working cylinder is due to the high temperature of air compressed therein, after the 15 engine has become heated and during the subsequent operation thereof.

The principal object of my invention is to provide improved insulation for the metallic conductor or conductors through which current is 20 supplied to the member of the plug which is heated to incandescence, as aforesaid, the insulating material being in the form of a granular powder which is packed about the conductor or conductors and the same being materially cheaper, and easier to apply, than the mica or ceramic insulators heretofore commonly used for insulating purposes in glow plugs.

A further object of my invention is to provide a glow plug wherein the high resistance igniting 25 member or part, which has to be of an alloy adapted to resist the action of burning gases upon it and is quite expensive, is reduced in length as compared with the length of such element heretofore commonly used in glow plugs; the said 30 igniting member being welded to short wire sections of good conducting material which in turn are welded to the insulated conductor or conductors enclosed within the shell or casing of the plug.

40 A further object of my invention is to provide various improvements in and relating to glow plugs hereinafter particularly referred to and described.

The drawing accompanying and forming a part 45 of this application illustrates the preferred embodiment of my invention, and the features wherein the same consists are particularly pointed out in the claims at the end of this specification.

50 In the drawing:

Figure 1 is a view showing a section upon a central longitudinally extending plane, of a glow plug made in accordance with my invention, both current supply conductors thereof being insulated.

Figure 2 is a sectional view similar to Figure 1 but showing a glow plug wherein a single current supply conductor is insulated from the outer shell or casing of the plug.

Figure 3 is a similar sectional view showing the 5 incandescent element of the plug as welded to short sections of wire which in turn are welded to insulated current supply conductors similar to those present in the form of my invention shown in Figure 1.

Referring now to the drawing, and first to Figure 1, the numeral 5 designates the outer metallic shell or casing of the plug, the same being hollow, and being exteriorly threaded so as to screw into a threaded opening in the head or cylinder wall 15 of the engine with which the plug is used; to which end it is provided with a hexagonal portion between its ends as shown.

Within the shell 5 are two current supply conductors 6, 7 in the form of rods extending longitudinally of the plug, and having each a longitudinally extending passage; the rods being made of copper or equivalent good conducting material. The inner ends of these rods are provided with enlarged heads 8, 9 which lie beneath a 25 mica wall 10 the periphery of which engages an annular ledge 11 within the lower end of the shell to thereby prevent upward movement of said rods. The outer end of the rod 6 is riveted or flanged so as to connect it to a circular conducting terminal 12 of copper which rests upon a mica member 13 at the outer end of the casing 5, and the outer end of the rod 7 extends through a hole 14 in the terminal 12 and is likewise secured to a similar circular terminal 15; the members 12 and 15 being insulated from one another by a disc 16 of mica or equivalent material. The periphery of the terminal 12 is slightly conical, and the terminal 15 has an upwardly extending threaded post 17 to receive a nut 18. A conical 30 ring 20 surrounds the terminal 12 and has a supply conductor 21 connected to it, whereby a conducting path is provided leading to the rod 6, and a conductor 22 terminating in a plate 23 having a passage for the post 17 provides a conducting 35 path leading to the rod 7. The ring 20 and plate 23 are spaced apart by an annular insulating member 24 from which it follows that tightening of the nut 18 acts to secure the conductors or leads 21, 22 to the plug. The heads 8, 9 provide 40 abutments which prevent upward movement of the rods 6, 7 during the final assembling of the plug when the outer ends of said rods are riveted or flanged over the terminal blocks 12, 15; and the head 8 prevents the rod 7 from being pulled 45

50

55

55

upward when the nut 19 is tightened to secure the supply leads 21, 22 to the plug terminals.

The space within the shell 5 and around the metallic conducting rods 6, 7 is filled with a powdered granular insulating material 25 supplied thereto and compacted within said space, after the rods and the inner mica wall 10 have been assembled with the shell; but before the outer insulating disc 13 is put in place to close the upper end of the shell; alumina (Al_2O_3) being the preferred granular material used and the same being pressed, rammed or otherwise compacted within the space aforesaid provided for its reception. The particles of said material do not, however, adhere to one another throughout the mass thereof, so that the separate grains are free to move upon and relative to one another as the plug (including the granular insulation thereof) expands and contracts, due to heating, when the plug is in use. Said compacted granular material fills all minute interstices of the space which it occupies and establishes intimate contact with the rods 6, 7 and with the interior of the wall of the shell or casing 5 and, being a better conductor of heat than insulating materials heretofore commonly used, it provides a relatively good path for the flow of heat from the rods to the shell and to the engine structure, and maintains the plug at a lower temperature than has heretofore commonly been the case in glow plugs.

In the form of my invention illustrated in Figure 1 a wire 26 which is of high electrical resistance extends from the upper end of the rod 6 (at which place it is welded or brazed to the rod) through the passage therein and to a point beyond the inner end of the plug, where it is coiled to form an igniting member or part 27 when the plug is in use; and then through the passage in the rod 7 to the upper end thereof where it is likewise welded or brazed to said upper end as indicated at 28.

In the form of my invention shown in Figure 2 the metallic shell 29 is roughened upon its inner surface, as by a thread 30, to secure a more firm bond between the granular material 31 and the casing; and an inwardly extending ledge 32 is provided at the inner end of the shell which supports a mica insulating member 33 through which the lower extremity of a single rod 34 extends, as shown. This rod is shown as corrugated externally to provide a better bond between it and the granular packing material and increase the area of contact between the two, and secure a better flow of heat from the rod to the granular material and to the shell or casing of the plug.

The upper end of the rod 34 extends beyond the outer end of the plug and is threaded to receive a nut (not shown) for fastening a supply conductor to the plug; and an internally threaded ring 35 is placed upon said upper end, the upper side thereof being in the same plane as the outer end of the shell 29 of the plug. A mica insulating member 36 rests upon the ring 35 and the outer end of the shell; and said insulating member 36 and the rod 34 are held in place (through the ring 35) by a gland nut 37 having an internally extending ledge which overlies said insulating member 36, as shown. Overlying said gland nut is a mica or equivalent washer 38 of insulating material; and a metallic nut 39 screwed upon the threaded outer end of the rod 34 serves to finish the assembling of the plug and form a seat for a supply conductor connector. The ring 35 prevents the rod 34 from being pulled upward as the nut 39 is tightened upon the terminal 34.

In the form of my invention illustrated in Figure 2 a high resistance wire 40 likewise extends from the outer end of the rod 34 (where it is welded or brazed in place as at 41) downward along a passage extending through said rod and beyond the inner end thereof, where it is made into a coil 42 which becomes incandescent when the plug is in use and forms an igniting member adjacent the inner end of the plug. The other end of said wire, however, and instead of returning through a second rod as in Figure 1, enters a passage 43 provided in the shell 29 and is staked or welded therein, as indicated at 44; the return circuit being through the engine structure as in grounded ignition systems. The granular material 31 is the same in this second type of plug, and serves the same purpose and has the same features of advantage, as the granular material 25 present and hereinbefore referred to in describing the form of my invention illustrated in Figure 1; except that the threaded interior of the shell and the corrugated outer surface of the rod 34 form a path of greater area for the flow of heat to the shell than is present in said first described form of my invention.

In the form of my invention illustrated in Figure 3 the shell or casing of the plug comprises a massive base part 45 threaded as shown to screw into a threaded opening in a cylinder wall; and a tubular part 46 the wall of which is made as thin as practicable fitting within the base and welded or brazed thereto at 47, and which tubular part extends above the upper end of the base farther than the upper parts of the shells in Figures 1 and 2.

The purpose of this comparatively long and thin-walled shell part is to restrain the flow of heat along the upper part of the plug and to the current supply cables (not shown) more effectively than is the case with the shorter and more massive upper end casings illustrated in Figures 1 and 2; the result being that the upper end of the plug and the cable terminals remain at a lower temperature in this form of my invention than in the forms hereinbefore described.

In this Figure 3 form the inner end of the two-part casing is provided with an inwardly extending ledge 48 which supports a metal plate 49, which in turn supports a mica insulating member 50 against which the inner ends of metallic conducting rods 51, 52 abut; these rods having passages at their inner ends within which short wire sections 53, 54 of a good heat conducting material are secured, as by welding at 55, 56. These wire sections extend through holes in the insulating member 50, and through larger holes (to avoid short circuiting the conducting rods) in the metallic plate 49; and the igniting member 57 of high resistance wire is butt welded to the extremities of the short wire sections as indicated at 58, 59.

The wire sections 53, 54 being of good heat conducting material, such as copper, but of small area in cross-section, it follows that they act to restrain the flow of heat from the igniting member 57 to the rods 51, 52; and that such heat as flows to the rods is dissipated to their larger mass, with the result that the rods remain cooler than though such short wire sections were not present. Heat from the rods is dissipated through the granular insulating material of the plug and to the plug shell substantially as hereinbefore explained.

The space between the rods 51, 52 and the tubular part 46 of the casing is filled with a granular

non-conducting packing material 60, the same as in the forms of my invention illustrated in Figures 1 and 2; and the outer ends of the rods extend through holes in a mica insulating member 61, and through larger holes in a metal plate 62; which parts are shown as held in place by an inturned ledge 63 at the outer end of the tubular shell part 48.

The numerals 64 and 65 designate the terminals of the plug to which supply conductors (not shown) are connected by any suitable connecting members; and a mica tube 66 within the lower part of the base 45 surrounds the inner ends of the rods 61, 62 to prevent them from being short circuited by accidental contact with the base. The granular packing material 68 extends inward to the insulating member 60 and fills the interstices between the inner ends of the rods and the mica tube 66 as shown at 67.

Having thus described and explained my invention I claim and desire to secure by Letters Patent:

1. A glow plug comprising a hollow cylindrical shell or casing adapted to fit within an opening in the wall of an internal combustion engine cylinder; two metallic rods within said shell and extending longitudinally thereof, and having terminals at the outer end of the plug; an igniting member to which current is supplied through said rods, and which member is located adjacent the inner end of the plug; two insulating members separate and independent of one another and located one at the inner and the other at the outer end of said shell, and having holes through which the ends of said rods extend; and a mass of non-conducting granular material filling the space between said rods and said shell.

2. A glow plug comprising a hollow cylindrical shell or casing adapted to fit within an opening in the wall of an internal combustion engine cylinder; two metallic rods within said shell and extending longitudinally thereof, and the inner ends of which rods are provided with short sections of wire of good heat conducting material; an igniting member welded to the extremities of said short wire sections, and which member is located adjacent the inner end of the plug; insulating members at the inner and outer ends of said shell and having holes through which the ends of said rods extend; and a mass of non-conducting granular material filling the space between said rods and said shell.

3. A glow plug comprising a hollow cylindrical shell or casing adapted to fit within an opening in the wall of an internal combustion engine cylinder; two metallic rods within said shell and extending longitudinally thereof, and each of which has a passage extending throughout its length; a wire of high electrical resistance extending through said passages and an intermediate portion of which forms an igniting member located adjacent the inner end of the plug; insulating members at the inner and outer ends of said shell and having holes through which the ends of said rods extend; and a mass of non-conducting granular material filling the space between said rods and said shell.

4. A glow plug comprising a hollow cylindrical shell or casing adapted to fit within an opening in the wall of an internal combustion engine cylinder; two metallic rods within said shell and extending longitudinally thereof; two circular terminals arranged one above the other and to which the outer ends of said rods are connected; said terminals being insulated from one another;

an insulating member at the upper end of said shell and whereby said terminals are insulated from said shell, said member having holes through which the outer ends of said rods extend; a second insulating member at the inner end of said shell and having holes through which the inner ends of said rods extend; an igniting member to which current is supplied through said rods, and which member is located adjacent the inner end of the plug; and a mass of non-conducting granular material filling the space between said rods and said shell.

5. A glow plug comprising a hollow interiorly threaded cylindrical shell or casing adapted to fit within an opening in the wall of an internal combustion engine cylinder; a corrugated metallic rod within said shell and extending longitudinally thereof; an igniting member located adjacent the inner end of the plug; a circuit including said rod as a part thereof, and through which current is supplied to said igniting member; insulating members at the inner and outer ends of said shell and having holes through which the ends of said rod extend; and a mass of non-conducting granular material filling the space between said rod and said shell and forming an insulator for said rod.

6. A glow plug comprising a hollow cylindrical shell or casing adapted to fit within an opening in the wall of an internal combustion engine, and which shell has an inwardly extending ledge at its inner end; an insulating member resting upon said ledge and having a hole therethrough; a metallic rod within said shell and extending longitudinally thereof and the inner end of which extends through the hole in said insulating member, and the outer end of which rod is threaded; an internally threaded ring in engagement with the thread upon said rod, and the upper surface of which lies in the plane of the upper end of said shell; a second insulating member resting upon the upper end of said shell and upon said ring, and which member has a hole extending therethrough through which the outer end of said rod extends; a gland nut in threaded engagement with the upper end of said shell and having an inwardly extending flange which engages the upper surface of said second insulating member to thereby hold the plug parts in assembled relation; an igniting member located adjacent the inner end of the plug; a circuit including said rod as a part thereof, and through which current is supplied to said igniting member; and a mass of non-conducting granular material filling the space between said rod and said shell and forming an insulator for said rod.

7. A glow plug comprising a hollow cylindrical shell or casing adapted to fit within an opening in the wall of an internal combustion engine cylinder; a metallic rod within said shell and extending longitudinally thereof, and which rod has a passage extending throughout its length; a wire of high electrical resistance extending through said passage and beyond the inner end of the plug to form an igniting member; a circuit including said rod as a part thereof, and through which current is supplied to said igniting member; and insulating means for insulating said rod from said shell.

8. A glow plug comprising a hollow cylindrical shell or casing adapted to fit within an opening in the wall of an internal combustion engine cylinder; a metallic rod within said shell and extending longitudinally thereof, and the inner end of which rod is provided with a short section of

wire of good heat conducting material; an igniting member welded to the extremity of said short wire section, and which member is located adjacent the inner end of the plug; a circuit including said rod and short wire section as parts thereof, and through which current is supplied to said igniting member; and insulating means for insulating said rod from said shell.

9. A glow plug comprising a hollow cylindrical shell or casing made up of a comparatively massive base part adapted to fit within an opening in the wall of an internal combustion engine cylinder, and a tubular part extending from said base part and having a comparatively thin wall to restrain the flow of heat to the outer end of the plug; a metallic rod within said shell and extending longitudinally thereof, and the inner end of which rod is provided with a short section of wire of good heat conducting material; an igniting member welded to the extremity of said short wire section, and which member is located adjacent the inner end of the plug; a circuit including said rod and short wire section as parts thereof, and through which current is supplied to said igniting member; and insulating means for insulating said rod from said shell.

10. A glow plug comprising a hollow cylindrical shell or casing made up of a comparatively massive base part adapted to fit within an opening in the wall of an internal combustion engine

30

cylinder, and a tubular part extending from said base part and having a comparatively thin wall to restrain the flow of heat to the outer end of the plug; two metallic rods within said shell and extending longitudinally thereof, and the inner ends of which rods are provided with short sections of wire of good heat conducting material; an igniting member welded to the extremities of said short wire sections, and which member is located adjacent the inner end of the plug; insulating members at the inner end of said base part and at the outer end of said tubular part and having holes through which the ends of said rods extend; and a mass of non-conducting granular material filling the space between said rods and said shell.

11. A glow plug comprising a hollow cylindrical shell or casing adapted to fit within an opening in the wall of an internal combustion engine cylinder; a metallic rod within said shell and extending longitudinally thereof; an igniting member located adjacent the inner end of the plug; a circuit including said rod as a part thereof, and through which current is supplied to said igniting member; insulating members at the inner and outer ends of said shell and having holes through which the ends of said rod extend; and a mass of granular alumina filling the space between said rod and said shell and forming an insulator for said rod.

HECTOR RABEZZANA. 30
